PORTABLE RECEPTACLE

Joseph L. Zarovy, Chicago, Ill.

Application July 1, 1935, Serial No. 29,316

6 Claims. (Cl. 184—1.5)

My invention relates to portable collector receptacles for use in draining liquids from elevated containers and more particularly it relates to an improved portable receptacle for receiving oil drained from the crank case of an automobile while in elevated positions for servicing.

In draining crank cases of automobiles, the automobile is usually positioned over a pit or is elevated to a distance of several feet from the floor. In either case, waste of the oil occurs if it is permitted to flow unguided into an open receptacle resting upon the floor, and since the draining operation requires considerable time, it is both laborious and time consuming to hold the receptacle in proximity to the outlet of a crank case during the draining process.

The invention has as one of its objects the provision of an improved closed portable receptacle of the kind described, and an improved extensible conduit adapted to receive oil from an elevated container and to deliver it without waste into a receptacle positioned on a floor.

Another object of the invention is the provision of an improved vertical extensible conduit and a mounting therefor on receptacles of the kind described.

Many other objects and advantages of the construction herein shown and described will be obvious to those skilled in the art from the disclosure herein given.

To this end my invention consists in the novel construction, arrangement and combination of parts herein shown and described and more particularly pointed out in the appended claims.

Referring now to the drawing:

Fig. 1 is an elevational view partially in section of a preferred embodiment of the invention; and

Fig. 2 is a view along the line 2—2 of Fig. 1.

Referring now more particularly to the drawing, the device is illustrated as comprising a can 10 of a capacity adapting it as a portable drainage receptacle for crank cases and other elevated containers. The can is constructed of any suitable material such as thin metal and is provided with a closed top or cover 11 preferably forming a liquid-tight joint with the body of the can.

A member 14, fastened to opposite sides of the can with its intermediate portion extending across and in spaced relation to the top of the can, is provided on one side with a handle piece 15. The handle piece may be of any suitable material but is preferably constructed of thin metal, curved as shown and fastened to the mem-

ber 14 by any suitable means such as welding or the like. The handle side of the member 14 is sufficiently narrow to be easily grasped with the hand and is made rigid by the connection therewith of the handle piece. The other side of the member 14 is wider and provides an opening through which a spout 13 projects. The spout 13 has a flanged end connected with the cover 11 by soldering or welding. The spout 13 is fastened to the member 14 by welding or the like and thereby adds rigidity to this end of the member. The open end of the spout 13 is so positioned and constructed as to form an overflow outlet before the can is completely filled.

An extensible conduit adapted to receive oil from containers at different elevations is shown in substantially retracted position. The conduit comprises a pipe 18 extending through and slidably fitting in aligned apertures 12 and 16, respectively formed in the cover 11 and the member 14.

A collar 17, fastened by welding, soldering or the like, cooperates with the bounding edges of the apertures 12 and 16 to hold the pipe 18 against lateral movement relative to the can. A projection 19, preferably taking the form of a ring soldered or welded to the pipe 18, provides a stop limiting the inward movement of the pipe to prevent its contact with the bottom of the can. A set screw 20, mounted on the collar 17, provides means for supporting the pipe 18 in any selected extended position.

A pipe section 23, telescoping within the pipe 18, provides an extension on the upper end of which is positioned a funnel 25. A projection 24, similar to the projection 19, provides a stop limiting the inward movement of the section 23 relative to the pipe 18. A shouldered collar 21 fastened on the upper end of the pipe 18 by welding or soldering provides a mounting for a set screw 22 by means of which the pipe section may be supported in any selected extended position relative to the pipe 18. The pipe 18 and pipe section 23, arranged as described, cooperate to form an adjustable vertical conduit adapted to be extended to bring the funnel 25 into proximity to the drain opening of a receptacle not shown.

Thus it will be seen that I have provided an improved vertically extensible conduit and mounting means therefor adapted to receive liquid from elevated containers and to deliver the same without waste into a portable receptacle positioned on a floor beneath the container.

Having thus described my invention, it is obvious that various immaterial modifications may be

made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a device of the kind described, a can having a closed top, a handle member extending over and in spaced relation to the top of the can, a vertically extensible conduit having its lower end terminating in said can, said conduit comprising a vertical pipe extending through registering openings in the top of the can and in the handle member, means providing a support for the pipe at a plurality of selected vertical positions, a pipe section supported by and forming an adjustable extension for the upper end of the pipe, said extension being capable of being raised to a plurality of sustained positions relative to its support, and means providing a funnel on the upper end of said extension.
2. A portable receptacle comprising a can having a closed top and an extensible conduit adapted to reach from the can to the drain opening of containers at a plurality of elevations, a member fastened to and projecting over the top of the can in spaced relation thereto, said member providing an opening in register with an opening in the top of the can, said conduit comprising a vertical pipe extending through said openings, means carried by said member providing a support for the pipe at a plurality of selected vertical positions, a pipe section supported by and forming an adjustable extension for the upper end of said pipe, means adapted to support said extension at a plurality of selected extended positions relative to said pipe, and means providing a funnel on the upper end of said extension.
3. A portable receptacle comprising a can having a closed top, a handle member having its ends rigidly connected to opposite sides of the can with its middle portion in spaced relation to the top of the can, said member and the top of the can respectively providing apertures in vertical alignment, an extensible conduit adapted to connect the can with a drain opening of an elevated container, said conduit comprising a pipe extending through said apertures, means carried by the can adapted to support the pipe at a plurality of sustained positions, a pipe section forming a telescoping extension for the upper end of said pipe, means carried by the pipe providing a support for said section at a plurality of extended positions, and means providing a funnel on the upper end of said section.
4. A portable receptacle comprising a can having a closed top, a member having its ends rigidly connected to opposite sides of the can with its middle portion in spaced relation to the top

of the can, said member and top of the can respectively providing apertures in vertical alignment, an extensible conduit adapted to connect the can with a drain opening of an elevated container, said conduit comprising a pipe extending through and closely fitting in said apertures, means carried by the can adapted to support the pipe at a plurality of selected positions, a pipe section forming a telescoping extension for the upper end of said pipe, means carried by the pipe providing a support for said section at a plurality of extended positions, stop means limiting the retractive movement of said pipe relative to the can, stop means limiting the retractive movement of said section relative to the pipe, and means providing a funnel on the upper end of said section.

5. A portable receptacle comprising a can having a closed top, a member having its ends rigidly connected to opposite sides of the can with its middle portion in spaced relation to the top of the can, said member and top of the can respectively providing apertures in vertical alignment, an extensible conduit adapted to connect the can with a drain opening of an elevated container, said conduit comprising a pipe extending through and closely fitting in said apertures, means carried by the can adapted to support the pipe at a plurality of selected positions, a pipe section forming a telescoping extension for the upper end of said pipe, means carried by the pipe providing a support for said section at a plurality of extended positions, means providing a funnel on the upper end of said section, and an upwardly inclined discharge spout for the can having its outlet at a level below the extreme top of the can to provide an overflow outlet.

6. A portable receptacle comprising a can having a closed top, a member having its ends rigidly connected to opposite sides of the can with its middle portion in spaced relation to the top of the can, said member and top of the can respectively providing apertures in vertical alignment, an extensible conduit adapted to connect the can with a drain opening of an elevated container, said conduit comprising a pipe extending through and closely fitting in said apertures, means carried by the can adapted to support the pipe at a plurality of selected positions, a pipe section forming a telescoping extension for the upper end of said pipe, means carried by the pipe providing a support for said section at a plurality of extended positions, stop means limiting the retractive movement of said pipe relative to the can, stop means limiting the relative movement of said section relative to the pipe, an upwardly inclined discharge spout for the can having its outlet at a level below the extreme top of the can, and means providing a funnel on the upper end of said section.

JOSEPH L. ZAROVY.
